United States Patent Office

Des. 228,351
Patented Sept. 11, 1973

228,351

BATTERY COVER

Jerome Louis Smentek, Milwaukee, Wis., assignor to
Globe-Union Inc., Milwaukee, Wis.

Filed Dec. 28, 1971, Ser. No. 213,234

Term of patent 14 years

Int. Cl. D13—02

U.S. Cl. D26—6

Fig. 1

Fig. 2

Fig. 3

Fig. 4

FIG. 1 is a perspective view of a battery cover incorporating my new design;

FIG. 2 is a top plan view of the battery cover shown in FIG. 1;

FIG. 3 is an end view of the battery cover illustrated in FIG. 1;

FIG. 4 is a view in side elevation of the FIG. 1 battery cover.

The broken line showing of a battery casing is for illustrative purposes only.

I claim:

The ornamental design for a battery cover, as shown and described.
